UNITED STATES PATENT OFFICE

2,625,112

ROTARY IMPELLER PUMP

Carl J. Stubau, Cleveland, Ohio, assignor to Borg-Warner Corporation, Chicago, Ill., a corporation of Illinois

Application December 24, 1948, Serial No. 67,111

2 Claims. (Cl. 103—138)

1

This invention relates to pumps and more particularly to rotary impeller pumps suitable for high pressure operation.

Rotary impeller pumps are widely used for pumping fluid where it is desired to provide a continuous pumping pressure subject to minimum fluctuation. In general such rotary impeller pumps comprise a rotor mounted on an axis eccentric to the axis of the pump chamber and having a plurality of impellers or vanes slidably mounted in radial slots formed in the rotor. The vanes are reciprocated in the slots as the rotor is rotated. While such pumps are generally satisfactory where used at low pressures, when used at high pressures, the leakage may become excessive, resulting in an appreciable decrease in the efficiency of the pump.

In accordance with this invention, it has been discovered that an important factor contributing to this leakage is the difficulty of maintaining a sufficiently close fit between the impeller vanes and the sides of the associated slots under all conditions encountered in operation. It will be understood that since these pumps are designed to operate under varying load conditions, they will consequently be operated under varying temperature conditions with resultant variations in the dimensions of the radial slots and the vanes journaled in the rotor. Thus, it has been the practice to provide a sufficient clearance between the sides of the slots and the vanes so that any expansion of the vanes which might occur in the operation of the pump or, conversely, any decrease in the width of the radial slots, will not cause the vanes to stick, that is, to seize the sides of the slots. This practice necessarily requires a certain looseness at normal operating temperatures and consequently the normal efficiency of the pump is necessarily low. It will also be apparent that machining the slots and finishing the vanes to the precise tolerances required is an expensive operation and furthermore requires careful fitting of the individual impeller blades to their respective slots.

It is an object of the present invention to provide a rotary impeller pump of improved efficiency.

It is a further object of this invention to reduce leakage losses between the impeller vanes and the sides of the slots in the rotor of a rotary impeller pump.

In accordance with one embodiment of this invention, spring loaded sealing means are provided in the rotor adjacent each of the slots and are adapted to engage the vanes in such manner

2

as to provide both a substantially constant bearing pressure and also a very effective seal. The combination bearing and sealing means, as applied to each vane, comprises a pair of shoes of suitable bearing material located in oppositely disposed, laterally extending recesses formed in the side walls of the slot and an elongated spring associated with each shoe for urging the shoes into contact with the surface of the adjacent side of the impeller vane.

Other objects and advantages of the present invention will be apparent from the following detailed description taken in conjunction with the drawings wherein:

15 Fig. 1 is an axial, cross-sectional view of a rotary impeller pump having combined sealing and bearing means in accordance with this invention;

20 Fig. 2 is an enlarged, sectional view taken along the line 2—2 of Fig. 1; and

Fig. 3 is an enlarged sectional view taken substantially along the line 3—3 of Fig. 2.

Referring now to the drawings, it will be seen that the pump comprises a main housing 10 within which is a casing 11 having a cylindrical bore 12. A hollow rotor 13 is journaled in the casing 11 and is rotatable by suitable means (not shown) on an axis eccentric to the axis of the cylindrical bore 12. Impeller vanes 14 and 15 of conventional design are slidably journaled in radially extending slots 16 and 17, respectively, formed in the rotor 13. In the operation of the pump, the rotation of the rotor and the sweeping movement of the associated impeller vanes cause 30 a difference in pressure to be produced between ports 19 and 20 formed in the housing 10. Since the rotor rotates on an axis eccentric to that of the bore 12, rotation of the rotor causes the impeller vanes to be reciprocated in their respective 35 slots.

It has been found in practice that while such a pump is quite efficient at low speeds of operation, when such a rotary impeller pump is operated at higher speeds to thereby develop a

40 greater pressure differential between the inlet and outlet ports, the efficiency of the pump drops markedly. An important factor in this loss in efficiency has been found to be leakage back through the slots 16 and 17 which, as is readily 45 evident in Fig. 1 of the drawings, communicate with each other through the hollow interior of the rotor.

Another important factor in the drop in efficiency at higher speeds is the increased friction and consequent heat. The friction, of course, in-

creases at higher operational speeds and causes heating of the pump parts with consequent dimensional changes therein. These dimensional changes result in the distortion and greater frictional engagement between the pump parts. Also, as the pump becomes hotter, the air pumped expands, causing an increase in the volume of the air without a commensurate increase in its weight and thus a net loss in the actual amount of air pumped. This expansion loss, as it might be termed, is, of course, significant only where the pump is used to pump materials such as gases having a high efficient of expansion with temperature.

In accordance with this invention, leakage through the slots is reduced to an insignificant quantity and at the same time friction between the sides of the slots and the impeller vanes journaled therein is minimized by providing sealing strips or shoes 23 and 24, respectively, on either side of each of the impeller vanes, the shoes being seated in suitable axially extending recesses 25 and 26, respectively, which are formed in the sides of each of the radial slots 16 and 17 in which the vanes are journaled, and which are preferably oppositely disposed.

The shoes 23 and 24 have a generally rectangular cross section, as is evident from Fig. 1, and, as shown in Fig. 2, are as long as the vanes. The shoes are urged into engagement with the vanes by elongated springs 27 and 28, respectively, positioned behind the shoes, that is, between the shoes and the rear walls of the recesses in which the shoes are positioned. The springs are made sufficiently strong to maintain the shoes in constant pressure contact with the vanes under all operating conditions. This requires usually that the springs contact the base of the shoes at a plurality of spaced points and also contact the rear walls of the recesses at a plurality of spaced points as shown in Fig. 2. Because of the high speed of reciprocation of the vanes, it is desirable that the shoes be formed of a material which not only provides a suitable lubricating and bearing surface and consequently one having a low coefficient friction, but also a material which will withstand wear and has high dimensional stability. The use of sealing shoes makes possible the use of materials having lower frictional coefficients than it is feasible to use for either the rotor or vanes. Thus, it has been found, in accordance with this invention, that a high lead bronze composition is satisfactory. Such a composition may more specifically comprise on the order of 19 to 23% lead, 76 to 80% copper, and the rest tin.

Referring to Fig. 2, it will be noted that a shoulder 29 is formed adjacent each end of the shoes on the side thereof facing the associated spring to retain the spring in position and to prevent the ends of the spring from touching the end walls 30 and 31 of the pump casing. While an elongated, flat or leaf type spring of generally sinusoidal or undulated longitudinal configuration has been illustrated, it will be understood that other types of resilient backing means might well be substituted. However, it has been found that the particular form illustrated is well suited to provide a substantially constant pressure and at the same time is readily assembled in the rotor with the sealing shoes. By making the over-all height of the shoes slightly greater than the depth of the recesses 25 and 26, it will be evident that the shoes will cooperatively provide the sole support for the impeller vanes and the vanes

will not engage the sides of the slots at all. This is best shown in Fig. 3.

While in the embodiment illustrated, sealing shoes have been shown positioned on either side of the impeller vanes, where the pump is intended to be operated in only one direction, it is sometimes feasible to omit one set of shoes, thus having only one shoe associated with each impeller blade. The consequent loss of efficiency is not serious for many applications. However, the desired form is that illustrated, since this illustrated form provides also a very effective bearing support for the impeller vane, reducing substantially the area of contact, and thereby the friction losses as well as enabling the use of suitable bearing material as hereinbefore set forth. A further advantage is achieved by the use of the sealing shoes in that the necessity of machining the rotor slots 16 and 17 to close tolerances is substantially avoided since the spring-pressed shoes automatically establish the minimum clearance required for sealing and at the same time the cooperating bearing pressures on either side of the vanes tend to center the vanes with respect to the slots. Thus the bearing surfaces are reduced to those actually contacted by the sealing shoes.

It has been found in actual tests that where the pump is provided with sealing shoes on either side of the vanes, a quite remarkable improvement in efficiency is obtained. This improvement is due to the improved seal and thereby resultant reduction in leakage and also to the considerable reduction in operating temperature of the pump achieved by minimizing friction. It has also been found that the seal is maintained over a wide range of operating temperatures. For example, in one conventional rotary impeller pump operating at 2250 R. P. M. it was found that the gas discharge was at the rate of 7.4 cubic feet per minute without the sealing shoes and 10.8 cubic feet per minute with the sealing shoes. At the same time it was found that the temperature of the air at discharge was approximately 290° F. without the shoes and 240° F. with the shoes. This reduction in temperature alone accounts for approximately a 5% increase in efficiency in addition to the increase in efficiency achieved by virtue of the sealing action, since over the usual operating range of such pumps a decrease in efficiency of approximately 1% is incurred for each ten degree rise in discharge temperature.

What is claimed is:

1. A rotary impeller pump including a rotor having a radially extending slot formed therein, and impeller vanes slidably disposed in said slot, a side wall of said slot having a laterally extending recess formed therein, a sealing shoe in said recess, and resilient means associated with said shoe for urging said shoe into contact with the side of said vane, said shoe comprising an elongated bar having a substantially rectangular cross-section and a shoulder formed adjacent each end for retaining the resilient means in position, the shouldered portion of said sealing shoe having a greater over-all height than the depth of said recess, whereby said shoe projects from said recess under all operating conditions of said pump and said resilient means comprising an elongated, generally flat spring having a substantially sinusoidal longitudinal configuration so as to provide a plurality of spaced contacts with the base of said shoe and the adjacent base of said recess whereby said shoe is uniformly urged into contact with said vane.

2. A rotary impeller pump including a rotor having a radially extending slot formed therein, an impeller vane slidably disposed in said slot, a side wall of said slot having a laterally extending recess formed therein, a sealing shoe in said recess, and resilient means interposed between the rear side of said shoe and the base of said recess for urging said shoe into contact with a side of said vane, said sealing shoe having a shoulder integrally formed therewith adjacent each end 10 of the rear side thereof, said shoulder portion having a greater height than the depth of said recess whereby said shoe projects from said recess under all operating conditions of said pump, and the length of said shoe being substantially 15 equivalent to the length of said vane.
